UNITED STATES PATENT OFFICE.

THOMAS SPENCER MILLER, OF SOUTH ORANGE, NEW JERSEY.

SEA-ANCHOR.

SPECIFICATION forming part of Letters Patent No. 727,175, dated May 5, 1903.

Application filed September 29, 1898. Serial No. 692,171. (No model.)

To all whom it may concern:

Be it known that I, THOMAS SPENCER MILLER, a citizen of the United States, and a resident of South Orange, in the county of Essex and State of New Jersey, have invented certain new and useful Improvements in Sea-Anchors, of which the following is a specification.

In the accompanying drawings, Figures 1 and 2 show a sea-anchor embodying my invention in two positions.

My sea-anchor, as shown, consists of two principal parts, each of which may be used independently of the other. One part consists of a cone 20, to which ropes 27 are connected and lead forward to a draft connection with the cable 1. This part corresponds in its function and method of operation with the ordinary sea-anchor in that it is a drag of constant area. The other or forward portion comprises the collapsible member as well as a spring 31 or extensible member, by which the rear portion is connected with the cable. This spring serves the double purpose of operating the collapsible member and of forming a yielding connection for the rear member with the vessel. Although I have shown a single spring performing these two functions, I do not wish to limit myself in that particular.

The collapsible part of the sea-anchor consists of bars 22 and 25, pivoted at their outer ends to each other. The bars 22 at their inner ends are pivoted to a central eye 23. The bars 25 at their inner ends are pivoted to the central plate 24. The bars 22 are covered with canvas or other flexible material 21. The central eye 23 is secured to the cable 1, which cable extends through said eye and at its rear end is secured to the plate 30. The plate 24 slides upon the rods 29, which connect the plate 30 with the plate 28, and has a draft-rod 26, to the rear end of which the ropes 27 are secured. Between the plate 28, which is secured to the rear ends of the rods 29, and the plate 24 is placed the helically-coiled spring 31. The rod 26 slides freely through the plate 28.

The operation of the sea-anchor is as follows: When the anchor is being towed through the water by the rope 1 at low speed, it will be in the position shown in Fig. 1, so as to

offer the maximum resistant area to the water. When its speed is increased, the spring 31 will yield to the increased resistance of the water, causing the forward frame and its cover 21 to collapse to the position shown in Fig. 2, so as to offer a decreased resistant area to the water. The compression of the spring is brought about both by the pressure upon the collapsible portion 21 and by the resistance of the rear portion 20 of the anchor. As the speed again decreases the spring 31 expands, bringing the additional area of the collapsing portion into use, and thus equalizing the strain and approximating to uniformity.

Having thus described my invention, what I claim, and desire to secure by Letters Patent, is—

1. A sea-anchor consisting of fixed and collapsible parts and mechanism whereby an increased resistance causes the collapsible part to collapse.

2. A sea-anchor provided with means for varying the resisting-surfaces to approximate a constant resistance at variable speeds.

3. A sea-anchor provided with means for changing the angle of the resisting-surfaces controlled by the speed whereby the pull of the anchor is more nearly equal at different speeds.

4. A sea-anchor provided with means for varying the resisting-surfaces controlled by the pressure upon said surfaces.

5. A sea-anchor provided with means for decreasing the area of the resisting-surfaces by an increase of pressure thereon.

6. A sea-anchor provided with an elastic member and connections from said elastic member to the resistant surfaces to hold them in place.

7. A sea-anchor having movable resistant surfaces adapted to be acted upon by the water to change their position, and an elastic support for said surfaces acting in opposition to the pressure of the water.

8. A sea-anchor having collapsible members and means whereby the pressure of water acts upon said members to close them proportionately to the pressure.

9. A sea-anchor consisting of a fixed and a collapsible part, and an elastic member connected with the collapsible part to hold it open.

10. In a sea-anchor, in combination, a fixed part, a collapsible part, an elastic member and connections between said elastic member and both of said parts whereby said collapsible part closes as said elastic member yields to the combined pressure of both of said parts.
11. A sea-anchor comprising a fixed and a collapsible part, and a draft-spring interposed between said parts.
- 10 12. A sea-anchor comprising a fixed and collapsible parts, and a draft-spring interposed between said parts, and connections whereby said spring acts to hold the collapsible member open.
13. A sea-anchor comprising radial arms supported at their inner ends from the anchor-rope, a flexible covering for said arms, a spring supported from the same rope, and

braces connecting the radial arms with the spring.

14. A sea-anchor comprising a central hub secured to the draft-rope, radial arms pivoted to the hub, a flexible covering for said arms, a frame secured to the draft-rope, a spring in said frame, and braces connecting said frame and the radial arms.

15. The combination with a sea-anchor, of a yielding or spring member inserted in the draft connection of said anchor and means whereby the effective area of said anchor is automatically varied as said member is compressed.

THOMAS SPENCER MILLER.
